UNITED STATES PATENT OFFICE

STEPHEN L. PALMER, OF TEANECK, NEW JERSEY

HOLLOW RUBBER ARTICLE AND METHOD OF MAKING THE SAME

Application filed January 30, 1929. Serial No. 336,209.

This invention relates to an improved hollow rubber article and method of making the same, and has for one of its important features the provision of such an article in the form of a water bag or bottle, the walls of which throughout the body and neck portions of the bottle are reinforced by a continuous layer or sheet of a material having the property of expansibility, such as a knit textile material. The essential feature of the neck portion, with which this invention is concerned is that of expansibility or distendability, whether created by the formation of the neck or by the material from which it is made.

Another important feature is to provide a hollow rubber article of this character, the contracted neck portion of which above and below the internal thimble having the threaded metal ferrule for the stopper consists of a plurality of superimposed laminations vulcanized together and each lamination having a part of the knit material incorporated therein. Thus, this portion of the bag or bottle is very strongly reinforced to prevent rupture or breakage of the walls under the severe twisting strains they are sometimes subjected to in the insertion or removal of the metal core to the mold.

Another important feature of the invention is to provide a new method for making hot water bags or bottles wherein a rigid core is used and which is primarily characterized by the formation of the bag with a continuous unbroken body wall and neck wall and the provision in said neck wall of expandible sections permitting of the withdrawal of the core through said neck at the top of the bag, and the expandible parts of the neck wall being subsequently folded inwardly upon intervening parts of said wall and cemented thereto.

The manufacture will be greatly expedited while at the same time the article will possess maximum strength and durability.

In the drawings, wherein I have illustrated a preferred embodiment of the invention as carried out in accordance with my new method, and in which similar refer-

ence characters designate corresponding parts throughout the several views,—

Figure 1 is a transverse sectional view through a mold showing the several layers of material, together with the mold core 55 adapted to be subjected to vulcanizing heat and pressure whereby the several layers are homogeneously united with each other;

Fig. 2 is a plan view illustrating the one-piece bag of knitted textile material, partly 60 broken away to illustrate the mold core assembled therein;

Fig. 3 is a transverse sectional view through the neck forming portion of the mold;

Fig. 4 is a similar sectional view showing 65 the expandible neck portions of the molded bag in folded position;

Fig. 5 is a fragmentary longitudinal section through the neck portion of the completed bag;

Fig. 6 is a detail horizontal section through the neck portion of a bag illustrating a slightly modified form thereof to permit expansion of the same in the withdrawal of the mold core, and

Fig. 7 is a fragmentary sectional view similar to Fig. 1 showing another alternative form of the article.

Referring in detail to the drawings, for purposes of illustration, I have conventionally represented upper end lower mold sections 5 and 6 respectively, the inner faces of which are concave or otherwise suitably shaped in accordance with the predetermined external cross sectional shape of the bag 85 walls. The lower mold section 6 is preferably stationary while the upper mold section 5 may be moved to and from a position in superposed relation to the lower section 6 by any suitable mechanical means. Each of these mold sections gradually decreases in width towards one of its ends, and beyond said tapering section terminates in the laterally diverging hollow wings indicated at 7 which project transversely of the intermediate connecting portion of the mold wall.

In conjunction with the two mold sections 5 and 6 a core 8 is employed which has opposite convex side faces substantially concentric to the opposed surfaces of the mold 100

sections 5 and 6 when the mold is closed. This core likewise tapers correspondingly to the tapered end portions of the mold sections 5 and 6 and terminates beyond said tapered 5 part in the solid metal wings indicated at 9 diverging from each other longitudinally of said core and projecting transversely in opposite directions from the intermediate body portion of the core. When the mold is 10 closed, the surfaces of the core wings 9 are substantially positioned in parallel relation to the corresponding internal surfaces on the mating wing sections 7 of the mold parts 5 and 6.

15 In Fig. 2 of the drawings, 10 indicates a bag having a continuous wall of expansible material such as a knitted textile material. This bag is also provided with a contracted end portion likewise terminating in the expansible wings indicated at 11, at opposite sides of the contracted neck of the bag. The core 8 is adapted to be inserted within this 20 knit bag, the sheets or layers of rubber composition material indicated at 12 being first applied to the opposite sides of the core. These rubber sheets are of such dimensions as to also cover the surfaces of the wing 25 portions 9 of the core, the edges of said sheets meeting at the opposite sides of the core in the central median plane thereof. The walls of the bag 10, when the core is thus inserted 30 may be slightly expanded and fit snugly upon the rubber sheets 12.

35 After the core, together with the rubber sheets 12 and the bag 10 have been thus assembled, a layer or sheet of rubber composition material shown at 13 is then laid upon the upper surface of the lower mold section 6 and a similar rubber sheet 14 is 40 likewise applied to the inner surfaces of the upper mold section 5. It is of course, understood that the rubber sheets are provided with a suitable mild adhesive solution evaporating under the application of heat so that the 45 rubber sheets will retain their applied positions on the surfaces of the mold sections 5 and 6 and the core 8 during the assembling operations.

50 The core 8 with the assembled sheets 12 and the bag 10 is then positioned on the rubber sheet 13 on the lower mold section 6, the wing extensions of the core at one side thereof of fitting within the hollow wing extensions 7 of the lower mold section. The upper mold section 5 is then moved to its closed position, the wing extensions 7 thereof receiving the 55 upwardly projecting parts of the wings 9 of the core. The vulcanizing heat is then applied and the meeting edges of the rubber sheets 12 and of the rubber sheets 13 and 14 are homogeneously united with each other, and at the same time, the rubber composition material of the inner and outer rubber sheets 60 unites through the interstices of the fabric material 10 so that this interposed layer of 65

knit textile material becomes in effect an integral part of the walls of the bag and forms an intermediate expansible reinforcement in said bag walls. It will be observed that this knit material extends throughout both the 70 body portion of the bag and the neck portion thereof without interruption in its continuity and through the medium thereof tensile strains upon the bag walls are more uniformly distributed to all parts of the bag. 75

After the lapse of a suitable period of time under the vulcanizing heat, the mold is opened and the core, together with the assembled parts of the bag is removed. After cooling, the core 8 may be readily withdrawn 80 from the bag as the wing portions 15 of the united rubber and textile sheets extending throughout the contracted neck portion of the bag will readily expand thereby permitting said neck portion to laterally expand 85 as the body portion of the core 8 is drawn therethrough. Therefore, notwithstanding the fact that in the molding operation, the contracted neck wall of the bag is continuous, the removal of the core can be readily 90 effected without danger of rupture of the bag walls. In this manner, I avoid the necessity of leaving an opening at the bottom 95 of the bag in accordance with prior art practice through which the core can be withdrawn. This opening must be subsequently sealed by vulcanizing a rubber strip therein, and is liable to result in structural weakness 100 of the bag at this point and resultant leaking.

After the core has been removed from the formed bag, a metal nipple 16 having an internal threaded bore 17 is inserted into the neck thereof, said nipple having its outer surface covered with fabric as indicated at 105 17'. This fabric is coated with a suitable cement. The wing extensions 15 of the bag are then folded inwardly upon the intermediate neck wall sections as clearly shown in Fig. 4 of the drawings, thus providing a plurality of laminations each having the reinforcing knitted fabric material incorporated therein and which extend throughout the neck portion of the bag. A suitable core 18 positioned on the end of a rod 19 which has an enlarged threaded end removably engaged in the threaded bore of the nipple 16 is also positioned within the flaring neck portion of the bag. The engaging surfaces of the superimposed laminations forming the neck wall 110 are coated with a suitable vulcanizing cement so that by the application of pressure, the said laminations are permanently connected with each other. Preferably in this operation a wire ring indicated at 21 is clamped about the neck wall at its smaller diameter in line with the nipple 16, said wire being preferably secured to and concealed by a narrow thin sheet of rubber 22 which is adhesively 115 secured at opposite sides of the ring to the 120 130

neck wall. The clamping ring 21 is contracted to such an extent that it is partially embedded in the outer surface of the neck wall to form an annular groove indicated at 5 20 therein.

In the above manner, a hot water bag or bottle is produced which is of seamless one-piece construction and while strongly reinforced in all positions thereof by the knit 10 fabric material 10, nevertheless possesses the desired flexibility in the body part of the bag permitting it to assume various shapes or forms when the bag is filled and pressure is applied thereto. The additional reinforcement 15 of the neck wall of the bag in the vicinity of the internal nipple or thimble 16 produced by the laminated construction of the neck walls affords the desired extra strength at this point to withstand severe twisting 20 strains and prevent rupture of the bag walls in inserting or removing the threaded plug or stopper. It will also be appreciated that my new method of molding such hollow rubber articles may be expeditiously carried out 25 by the use of relatively simple apparatus which may be operated by unskilled labor. Thus such hot water bags or bottles, while possessing very material advantages over similar articles as heretofore produced in this 30 art may nevertheless be manufactured at comparatively small cost.

The bag may also be produced by the method above described without necessarily using the rubber sheets between the surfaces 35 of the mold core 8 and the walls of the fabric bag 10. Thus, as indicated in Fig. 7 of the drawings, only the rubber sheets 14 interposed between the fabric bag and the walls of the mold sections 5 and 6 need be used. 40 Under the application of heat and pressure, the rubber will be reduced to a more or less fluid condition, and it will thoroughly permeate the fabric bag 10, entering through the inner surfaces of the bag walls so that the 45 fabric material becomes substantially incorporated in an intermediate position within the body of rubber when the latter again solidifies. Thus, there will be produced what is in effect a single walled bag or receptacle 50 in which the knitted fabric material is homogeneously incorporated.

The substantial reinforcement of the rubber walls of the bag by the central continuous layer of knit textile fabric is of particu- 55 lar advantage and important in connection with hot water bags or receptacles which must withstand very heavy pressures, as for instance, such receptacles as are designed for the purpose of rectal injection. It has been 60 found that by reason of this knit fabric reinforcement, the rupture or breakage of the flexible wall of the bag under very severe pressures, is prevented.

In Fig. 6 of the drawings, I have illus- 65 trated a slightly modified form of the inven-

tion wherein the neck portion of the bag may be provided with sufficient material to permit of the formation therein of a large number of circumferentially extending overlapping pleats 23 adapted to be folded closely upon each other and locked together to thus produce the laminated construction of the neck wall as above referred to. 70

It is also evident that the invention as herein described is susceptible to numerous other modifications both in the construction of the bag and in the specific method of producing the same. Accordingly, it is to be understood that I reserve the privilege of resorting to all such legitimate changes as may be fairly embodied within the spirit and scope of the invention as claimed. 75 80

I claim:

1. The method of making a hollow article of vulcanized rubber which consists in assembling sheets of rubber composition and knitted fabric material to constitute opposite side walls of the bag together with an interposed rigid core within a suitable mold and forming said sheets under the application of heat 85 and pressure to vulcanize the lateral edges of the bag walls together and homogeneously unite the several sheets with each other and forming the bag at one end with a contracted neck portion having relatively expansible parts permitting the withdrawal of the core through said neck portion of the bag, and subsequently folding said expansible portions upon the contiguous portions of the neck wall and cementing the same together. 90 95

2. The method of making a water bag which consists in first assembling a mold core within a one-piece bag of knitted fabric material, then applying rubber sheets to the sides of the bag wall and subjecting the same within a mold to the action of heat and pressure whereby said rubber sheets are homogeneously united with each other to form a bag having a contracted neck and the rubber is caused to penetrate the interstices of the knitted fabric to the inner surfaces of the bag wall, and finally withdrawing the mold core by expanding the contracted neck portion of the bag. 100 105 110

3. The method of making a rubber article which consists in molding the body and neck portions of blanks forming opposite sides of the article over a core and vulcanizing said blanks together at their meeting edges, simultaneously forming in the neck portion of each blank expansible extensions permitting of the removal of the core through said neck portion of the article. 115 120 125

4. A water bag having walls consisting of rubber composition material and an interposed reinforcing layer of woven fabric material vulcanized together, and said bag having a contracted neck portion consisting of parts of said bag walls relatively folded into 130

superimposed laminations and permanently secured together.

5. A hollow article consisting of a reinforcing hollow structure having its walls formed of textile fabric material and provided with a contracted neck portion at one end, and an outer layer of rubber encasing the walls of said reinforcing structure and interlocked therewith through the interstices 10 of said fabric walls to inseparably unite the reinforcing structure and said rubber layer with each other, the contracted neck portion embodying parts of the rubber layer and the reinforcing fabric walls relatively folded 15 into superimposed laminations permanently secured.

6. A hollow article of reinforced rubber consisting of a body portion and a neck portion, the neck portion having relatively folded 20 parts held in superposed laminations permanently secured together.

7. The method of making hollow articles of reinforced rubber having an enlarged body portion and a restricted neck portion, which 25 consists in molding a stretchable knitted fabric material and rubber on all sides around a core having an enlarged body portion and a restricted neck portion, to form a hollow article with an enlarged body portion and a 30 restricted neck portion in its completed molded state, and then stretching the formed restricted neck portion of the article to an extent to permit withdrawal of the enlarged body portion of the core through said neck 35 portion of the article, all parts of the article remaining in a completed molded state during the withdrawal of the core therefrom.

8. The method of making hollow articles of reinforced rubber having an enlarged body portion and a restricted neck portion which 40 consists in molding a stretchable knitted fabric and rubber on all sides around a core having an enlarged body portion and a restricted neck portion to form a hollow article having 45 an enlarged body portion and a restricted neck portion, said article having around its restricted neck portion overlapping folds, then opening the folds relatively of each other and stretching the formed restricted 50 neck portion of the article to an extent to permit the enlarged portion of the core to be withdrawn through the neck of the molded article, all parts of the article remaining in a completed molded state during the withdrawal of the core therefrom.

In testimony that I claim the foregoing as my invention, I have signed my name hereto.

STEPHEN L. PALMER.
